UNITED STATES PATENT OFFICE

164,415

CONTAINER FOR CANDLES

Oscar D. Guilfoil, Jr., Syracuse, N. Y.

Application March 14, 1950, Serial No. 8,518

Term of patent 14 years

(Cl. D58—25)

To all whom it may concern:

Be it known, that I Oscar D. Guilfoil, Jr., a citizen of the United States, residing at Syracuse, State of New York, have invented a new, original, and ornamental Design for Container for Candles, of which the following is a specification, reference being had to the accompanying drawing, forming part hereof.

I claim:

The ornamental design for a container for candles, as shown and described.

OSCAR D. GUILFOIL, JR.
